(Continued)

FIG. 22 is an enlarged sectional view taken along line 22-22 shown in FIG. 19;
 FIG. 23 is a perspective view of a third embodiment of a pipette tip for a laboratory instrument;
 FIG. 24 is a front view thereof;
 FIG. 25 is a rear view thereof;
 FIG. 26 is a right side view thereof;
 FIG. 27 is a left side view thereof;
 FIG. 28 is a top view thereof;
 FIG. 29 is a bottom view thereof;
 FIG. 30 is a cross sectional view taken along line 30-30 shown in FIG. 28;
 FIG. 31 is an enlarged sectional view taken along line 31-31 shown in FIG. 30;
 FIG. 32 is an enlarged sectional view taken along line 32-32 shown in FIG. 30;
 FIG. 33 is an enlarged sectional view taken along line 33-33 shown in FIG. 30;
 FIG. 34 is a perspective view of a fourth embodiment of a pipette tip for a laboratory instrument;
 FIG. 35 is a front view thereof;
 FIG. 36 is a rear view thereof;
 FIG. 37 is a right side view thereof;
 FIG. 38 is a left side view thereof;
 FIG. 39 is a top view thereof;
 FIG. 40 is a bottom view thereof;
 FIG. 41 is a cross sectional view taken along line 41-41 shown in FIG. 39;
 FIG. 42 is an enlarged sectional view taken along line 42-42 shown in FIG. 41;
 FIG. 43 is an enlarged sectional view taken along line 43-43 shown in FIG. 41;
 FIG. 44 is a perspective view of a fifth embodiment of a pipette tip for a laboratory instrument;
 FIG. 45 is a front view thereof;
 FIG. 46 is a rear view thereof;
 FIG. 47 is a right side view thereof;
 FIG. 48 is a left side view thereof;
 FIG. 49 is a top view thereof;
 FIG. 50 is a bottom view thereof;
 FIG. 51 is a cross sectional view taken along line 51-51 shown in FIG. 49;
 FIG. 52 is an enlarged sectional view taken along line 52-52 shown in FIG. 51; and,
 FIG. 53 is an enlarged sectional view taken along line 53-53 shown in FIG. 51.
 The dot-dash lines in the drawings are sectional indicators that form no part of the claimed design.
